CALCULATOR

William A. Jermy, Los Angeles, Calif.

Application November 21, 1938, Serial No. 241,554

8 Claims. (Cl. 235—74)

My invention relates to a calculator or calculating instrument.

One of the principal objects of this invention is to provide a device of this class for adding and subtracting common fractions, or their equivalents, and mixed numbers, and for adding and subtracting the same rapidly and accurately.

Another important object of this invention is to provide a device of this class which is simple and economical of construction proportionate to the functions adapted to be performed thereby, one which is compact and durable, and one which is simple to operate.

A further important object of this invention is to provide novel means of stopping the opposite rotation of the calculating or operating member in the same position, and also means of checking, at the same location, the movement of a stylet used for operating said member.

An important object also is the provision of means, in an instrument of this class, whereby the stylet may be guided directly from the stylet guide groove of one series of characters to a similar groove of another or multiple or fractional series of characters.

With these and other objects in view, as will appear hereinafter, I have devised a calculator, as will be hereinafter described in detail and particularly set forth in the appended claims, reference being had to the accompanying drawing and to the characters of reference thereon, which form a part of this application, in which:

Fig. 1 is a front or top view of my calculator in a preferred form of construction;

Fig. 2 is a similar view thereof, but in section, with the section taken through 2—2 of Fig. 3;

Fig. 3 is a transverse section taken through 3—3 of Fig. 1;

Fig. 4 is a fragmentary transverse section taken through 4—4 of Fig. 1;

Fig. 5 is a view of the stylet which may be used; and,

Fig. 6 is a fragmentary front or top view of the calculator in a moved position.

My calculator is enclosed in a casing or frame 1, which may be circular in shape, as shown, and which is provided primarily with three shallow circular recesses 1^a, 1^b and 1^c, the two latter preferably within the circular outline or in the middle of the former. In these shallow recesses are rotatably mounted the calculating or operating members 2, 3 and 4, all of which are preferably discs or flat annular members. The operating member or annulus 2 is held in place by a retaining annular plate or ring 5, and the mem-

bers 3 and 4 are held in position by a circular retaining plate 6. These plates may be secured in place by screws 7 or other suitable means.

As shown in the drawing, the recess 1^a, in which the annulus 2 is located, is annular and is located near the periphery of the circular casing or frame. The calculating or operating member 2 is located centrally or guided at its radially inner edge by the radially inner wall of the recess 1^a. At the whole of said inner edge of the member 10 or annulus 2 are equally spaced notches 2^a, equal in number and positioned in radial alignment with characters 2^b. The notches 2^a are positioned opposite and accessible through a circular slot or channel A, formed between the adjacent edges of the retaining plates 5 and 6. The characters, in this instance are fractions advancing in sixty-fourths and ranging from zero (0) to sixty-three sixty-fourths (63 $\frac{3}{4}$), and are equally spaced over the whole circumference. If desired, the 20 decimal equivalents of these fractions may be placed opposite the same. The outside diameter of the annulus is considerably smaller than the outer diameter of the recess 1^a. At the periphery is a stop lug 2^c, which extends beyond the periphery such a distance only that the annulus may be freely rotated, with the lug clearing the outer or adjacent wall of said recess. In said outer wall is an arcuate notch 1^d within which is seated to slide a movable stop 8. This movable stop extends between the bottom of the notch 1^d and the outer wall of the annulus, and is so constructed that the lug 2^c is not permitted to pass. The width of the lug and the length of the stop are such that the rotary movement of 30 the disc in opposite directions is checked at substantially the same position. This position is indicated by the character "0" on the disc, which registers with an index portion or may be seen through a window 5^a. This window is shaped 40 preferably so that the fractions and their decimal equivalents may be seen therethrough.

On the face of the retaining plate 5 are characters or fractions 5^b which correspond identically with the characters 2^b and are similarly 45 spaced. These characters 5^b increase progressively in value from the window 5^a and are intended to evaluate the notches 2^a extending from the window to the fraction designation in question.

The members or discs 3 and 4 may be identical in construction. They are rotatably mounted on central hubs 1^e and 1^f, and are provided at their peripheries with equally spaced notches 3^a and 4^a, respectively, which may be seen and are ac- 55

cessible through arcuate, substantially semicircular, slots 6^a and 6^b in the plate 6 . These discs have unit characters 3^b and 4^b , respectively, ranging from zero (0) to nine (9), positioned opposite site ten (10) of said notches, and which may register with index portions or may be seen through windows 6^c and 6^d , respectively, in the retaining plate 6 . Each disc has also a stop lug, designated 3^c and 4^c , respectively, for stopping or checking the rotation of the respective disc, when rotated in either direction. These lugs 3^c and 4^c are preferably radial elongations of portions between adjacent notches 3^a and 4^a , respectively. A portion, that is, approximately one-half, of the recesses 1^b and 1^c is enlarged, as indicated by 1^g and 1^h , respectively, to permit free movement of said stop lugs for approximately one-half revolution of the discs 3 and 4 . At the ends of these diametrical enlargements are provided stops or shoulders, those in the recess 1^b being designated 1^i and 1^j , and those in the recess 1^c being designated 1^k and 1^l , the first mentioned shoulder in each recess stopping the discs in their zero (0) positions, as seen through the windows, and the last mentioned shoulder in each recess stopping said discs when the numeral nine (9) is seen through the windows.

The retaining plate 6 has a short slot or channel 6^e which is substantially an elongation of the slot or channel 6^a but spaced from the end thereof. This slot 6^e is of a length that the disc may be rotated one notch by the stylet, shown in Fig. 5. The end of the channel 6^e nearest the channel 6^a is connected with the channel A opposite the window 5^a , so that the stylet may be moved readily from the notch in the disc 2 , opposite the window 5^a , into a notch in the disc 3 for rotating the latter one notch clockwise, or so that the stylet may be moved from a notch in the disc 3 into the notch in the member 2 opposite the window 5^a .

Similarly, the retaining plate 6 is provided with another short arcuate slot or channel 6^g for moving the disc 4 one notch. The end of the channel 6^g nearest the channel 6^b is connected by a diagonal channel 6^h with the opposite end of the channel 6^a , so that the stylet may be readily moved from a notch of the disc 3 into a notch of the disc 4 , or in the opposite direction.

At the edge of the retaining plate 6 is mounted a slide 9 which has an arcuate movement equal only to the distance of adjacent notches. This slide has a retaining portion 9^a which may ride in a groove 6^i at the underside of the plate 6 adjacent its periphery. This slide also has a projection 9^b which bridges the channel A and may be shifted by the stylet to one of two positions so that either side of the projection will be in alignment with the index portion or window 5^a .

The several movable members are preferably tightly fitted in their respective recesses or guides, or provided with suitable friction washers or devices, as indicated by 10 , that, at least, a slight force is required to move them.

My calculator is operated as follows for the addition of fractions:

The discs 2 , 3 and 4 are first moved to their zero (0) positions. It is now assumed that the fractions $\frac{5}{64}$, $\frac{21}{32}$, and $\frac{3}{8}$ are to be added. The stylet is inserted through the groove or channel A into the notch 2^a opposite the fraction $\frac{5}{64}$, designated 5^b on the member 5 , and the disc is then rotated clockwise until the movement of this stylet is checked by the slide 9 . This brings the fraction $\frac{5}{64}$ on the member 2 , opposite the window 5^a .

The stylet is then inserted into the notch 2^a opposite the fraction $\frac{21}{32}$ on the member 5 , and the disc 2 again rotated clockwise until further rotation is checked by the slide. The sum of $\frac{5}{64}$ is found opposite the window 5^a . The stylet is then inserted into the notch opposite $\frac{3}{8}$ and the disc again rotated clockwise, but this time the rotation of the disc 2 is checked before the stylet engages the slide 9 . A zero (0) in the window 5^a indicates that the sum is greater than a whole number. With the stylet still in the same notch, the disc 2 is rotated counterclockwise until the stylet engages the bottom of the slide 9 and moves it to its opposite position. The fraction $\frac{1}{64}$ is then seen through the window 5^a . The stylet is then moved into the diagonal slot 6^e and to its limit in the slot or channel 6^e . Such movement shifts the disc 3 , one notch, so that the unit character "1" is seen or registers through the window 6^c . Thus, the sum of the above fractions is seen to be 1 and $\frac{1}{64}$.

If the disc 3 cannot be rotated clockwise in the channel 6^e , or if, when desiring to add a whole number less than 10 , the clockwise rotation of the disc 3 is checked before the stylet is moved to the end of the slot 6^a , this indicates that the sum is greater than a unit member on the disc 3 , and that the disc 4 must be moved to register another digit and the whole sum. If, when inserting the stylet in a notch in the disc 3 , the disc is rotated clockwise without engagement of the stylet with the end portion of the slot or channel 6^a , that is, if the movement of the stylet is checked before it reaches the end of the slot 6^a , said disc, with the stylet in the same notch, is rotated counterclockwise, and moved through the diagonal slot 6^h into the short channel 6^g , thereby moving the disc 4 one notch. The sum of the whole numbers is seen through the windows 6^d and 6^e .

To subtract with my calculator, the foregoing steps are reversed. Assuming that the aforementioned fractions are to be progressively subtracted from $1\frac{1}{64}$, the device is adjusted so as to read accordingly on the discs 3 and 2 . The slide 9 is shifted to its limit in a clockwise direction. The stylet is then inserted into the notch 2^a opposite the window 5^a and the disc 2 rotated in a counterclockwise direction until the stylet is opposite $\frac{3}{64}$ designated 5^b . Through the window 5^a is seen the remainder $\frac{1}{2}$. The stylet is then again inserted into the notch opposite the window 5^a . If it is now attempted to rotate the disc 2 the desired amount in a counterclockwise direction, such rotation is checked. The disc 2 is then returned to its initial position with the stylet against the slide. The stylet is then shifted to the bottom of the slot 6^e and moved counterclockwise. This moves the disc 3 one notch and brings a zero (0) to the window 6^c . The stylet is also moved through the slot 6^h to its limit, thereby shifting the slide in a counterclockwise direction and causing the stylet to move into the notch 2^a opposite the window 5^a . The disc 2 is then rotated clockwise until the stylet is opposite the fraction $\frac{3}{2}$. In the window 5^a will be seen the remainder $\frac{3}{8}$. The slide is then again shifted to its extreme clockwise position and the stylet inserted into the notch opposite the window 5^a and the disc 2 rotated in a counterclockwise direction until the stylet is opposite the fraction $\frac{3}{8}$ of the characters designated 5^b . The remainder in the windows 5^a and 6^c is zero (0).

Though I have shown and described a particular construction, combination and arrange- 78

ment of parts and portions, I do not wish to be limited to the same, but desire to include in the scope of my invention the construction, combination, and arrangement substantially, as set forth in the appended claims.

I claim:

1. An instrument of the class described, comprising a frame having an arcuate channel in its face and equally spaced characters on said face adjacent the channel, an operating member rotatably mounted in the frame and provided with notches positioned opposite the channel and spaced to register with said characters, said member being also provided with characters positioned adjacent the notches and corresponding to the first characters, said frame having an index portion with which the characters on said member are adapted to register, said member having a radially extending lug adapted to make a complete revolution, and a movable stop mounted on the frame in the path of said lug adapted to be moved in opposite directions by the operating member for stopping, at the same position, the opposite rotations of the operating member.

2. An instrument of the class described, comprising a frame having an arcuate channel in its face and equally spaced characters on said face adjacent the channel, and an annular operating member rotatably mounted in the frame and provided at its inner edge with radially inwardly directed notches positioned opposite the channel and spaced to register with said characters, said member being also provided with characters positioned radially outwardly from the notches and corresponding to the first characters, said frame having an index portion radially outwardly from the channel with which the characters on said member are adapted to register, said member having a radially extending lug at its periphery adapted to make a complete revolution, and a movable stop mounted on the frame in the path of said lug adapted to be moved in opposite directions by the operating member for stopping, at the same position, the opposite rotations of the operating member.

3. An instrument of the class described, comprising a frame having an arcuate channel in its face and equally spaced characters on said face adjacent the channel, an operating member rotatably mounted in the frame and provided with notches positioned opposite the channel and spaced to register with said characters, said member being also provided with characters positioned adjacent the notches and corresponding to the first characters, said frame having an index portion with which the characters on said member are adapted to register, said member having a radially extending lug adapted to make a complete revolution, a movable stop mounted on the frame in the path of said lug adapted to be moved in opposite directions by the operating member for stopping, at the same position, the opposite rotations of the operating member, and a slide mounted on the frame and extending over the path of the notches and adapted to be moved the distance of adjacent notches.

4. An instrument of the class described, comprising a frame having an arcuate channel in its face and equally spaced characters on said face adjacent the channel, and an annular operating member rotatably mounted in the frame and provided at its inner edge with radially inwardly directed notches positioned opposite the channel and spaced to register with said characters, said

member being also provided with characters positioned radially outwardly from the notches and corresponding to the first characters, said frame having an index portion radially outwardly from the channel with which the characters on said member are adapted to register, said member having a radially extending lug at its periphery adapted to make a complete revolution, a movable stop mounted on the frame in the path of said lug adapted to be moved in opposite directions by the operating member for stopping, at the same position, the opposite rotations of the operating member, and a slide mounted on the frame and extending over the path of the notches and adapted to be moved the distance of adjacent notches.

5. An instrument of the class described, comprising a frame having an arcuate channel in its face and equally spaced characters on said face adjacent the channel, an operating member rotatably mounted in the frame and provided with notches positioned opposite the channel and spaced to register with said characters, said member being also provided with characters positioned adjacent the notches and corresponding to the first characters, said frame having an index portion with which the characters on said member are adapted to register, said member having a radially extending lug adapted to make a complete revolution, a movable stop mounted on the frame in the path of said lug adapted to be moved in opposite directions by the operating member for stopping, at the same position, the opposite rotations of the operating member, a slide mounted on the frame and extending over the path of the notches and adapted to be moved the distance of adjacent notches, said frame having another arcuate channel in its face and equally spaced characters on said face adjacent the arcuate channel, and another operating member rotatably mounted in the frame and also provided with notches positioned opposite the second channel and spaced to register with the latter characters, the latter operating member being also provided with characters corresponding to the characters adjacent the arcuate channel, said frame having a second index portion with which the characters on said second operating member are adapted to register, the face of the frame having a short third channel, concentric with the second channel, connected with the first channel, opposite the first index portion.

6. An instrument of the class described, comprising a frame having an arcuate channel in its face and equally spaced characters on said face adjacent the channel, and an annular operating member rotatably mounted in the frame and provided at its inner edge with radially inwardly directed notches positioned opposite the channel and spaced to register with said characters, said member being also provided with characters positioned radially outwardly from the notches and corresponding to the first characters, said frame having an index portion radially outwardly from the channel with which the characters on said member are adapted to register, said member having a radially extending lug at its periphery adapted to make a complete revolution, a movable stop mounted on the frame in the path of said lug adapted to be moved in opposite directions by the operating member for stopping, at the same position, the opposite rotations of the operating member, a slide mounted on the frame and extending over the path of the notches and adapted to be moved the distance of adjacent notches.

notches, said frame having a second arcuate channel in its face radially inwardly from the first channel and provided with equally spaced characters on said face adjacent the second arcuate channel, and another operating member rotatably mounted in the frame and also provided with notches positioned opposite the second channel and spaced to register with the latter characters, the latter operating member being also provided with characters corresponding to the characters adjacent the second arcuate channel, said frame having a second index portion with which the characters on said second operating member are adapted to register, the face of the frame having a short third channel, concentric with the second channel, connected with the first channel, opposite the first index portion.

7. An instrument of the class described, comprising a frame having an arcuate channel in its face and equally spaced characters on said face adjacent the channel, an operating member rotatably mounted in the frame and provided with notches positioned opposite the channel and spaced to register with said characters, said member being also provided with characters positioned adjacent the notches and corresponding to the first characters, said frame having an index portion with which the characters on said member

are adapted to register, said member having a radially extending lug, and a movable stop mounted on the frame in the path of said lug adapted to be moved in opposite directions by the operating member for stopping the opposite rotations of the operating member.

8. An instrument of the class described, comprising a frame member, an operating member rotatably mounted on the frame member and provided with circumferentially spaced notches, the frame member having spaced characters with which the notches are adapted to register, the operating member being also provided with characters positioned adjacent the notches and corresponding with the first characters, said frame member having an index portion with which the characters on the operating member are adapted to register, and lug and stop means in association with said members, said means having a lug fixed with respect to one of the members, said means including a stop having a limited movement with respect to the other member, said lug and stop being so constructed and arranged and having such relative movement that the operating member is adapted to make a complete revolution in opposite directions.

WILLIAM A. JERMY.
